INVENTOR,

Atmos Calleson,

BY John Edward,

ATTORNEY.

UNITED STATES PATENT OFFICE.

AMOS CALLESON, OF BROOKLYN, NEW YORK.

SEALING APPLIANCE.

1,353,628.

Specification of Letters Patent. Patented Sept. 21, 1920.

Application filed February 21, 1920. Serial No. 360,344.

To all whom it may concern:

Be it known that I, AMOS CALLESON, a citizen of the United States, residing at Brooklyn, in the county of Kings and State 5 of New York, have invented certain new and useful Improvements in Sealing Appliances, of which the following is a specification.

This invention relates to devices for attaching closures to bottles of the class in 10 which an annular expansible throat-forming series of closure attaching segments, into which the bottle head with the superimposed closure is forced, is embraced by a yielding resistance means—such as a spring. The invention contemplates a novel device of this 15 class in which all parts of the resistance means yield together or as one when the bottle head is forced into the throat in the act of affixing a closure, instead of successively, 20 as where the resistance means is a series of parallel spring rings or a helical spring whose coils are wound progressively along and around the axis of the throat, certain disadvantages of which are avoided by my 25 construction, for instance, the rocking of the segments so that they do not remain parallel with the throat axis during the entering and withdrawing movements of the bottle head, and excessive friction, which sooner or later 30 coact to produce wear of the parts and cause breakage of bottles.

My invention distinguishes from prior art devices in its class in that it comprehends 35 means to apply, to portions of the series of segments in planes remote from each other and transverse of the axis of the series, yielding resistance to the expansion of the series including a spring ring embracing said 40 series and cut by both said planes and being rigid from one such plane to the other. I prefer to employ a plurality of these rings, 45 concentric and laminated, and to treat the ring or rings in certain novel respects with a view to producing additional advantageous results, all as will hereinafter appear.

In the drawing,

Figure 1 shows in section a sealing head 50 of a bottle sealing machine and my improved closure affixing device therein;

Fig. 2 is a plan of the device;

Fig. 3 is a side elevation of the device as shown in Fig. 1;

Fig. 4 is a vertical sectional view of the device, showing a modification; and

Fig. 5 is a perspective view of one of the 55 spring rings.

A housing *a* for the closure-affixing device is formed between the end of the stem *b* and a cup-shaped holder *c* secured on the stem by the screw *d*, *e* being the mouth of the holder through which the bottle head and superimposed closure are admitted; *f* is a plunger which as the bottle and superimposed closure (which is assumed in the present instance to be a crown of the well known type shown in broken lines at *A*) enter the holder *c* opposes yielding resistance thereto. The bottom of the housing *a* is formed by an apertured liner disk *g*; at the top of the housing is a hardened apertured dish *h* herein shown inlaid in the lower end of the stem *b*.

i is an annular expansible throat-forming series of segments, preferably made of hardened metal and formed substantially the same as in my Patent No. 1,299,551, for example; when this series of segments expands or contracts as the bottle head and superimposed closure enter or leave the throat *j* thereof, the wear incident to their movement is assumed by the disk *h*.

The means for opposing yielding resistance to the expansion of the series of segments is in the illustrated embodiment three concentric laminated spring rings *k*; they are preferably, as shown, split rings, arranged so as to break joints, and to keep them in a definite relation to each other I may provide a projection *l* on one ring (as by driving the metal by a sharp instrument from one side so as to produce a protuberance at the other) to engage in the split *m*, or an enlargement *n* thereof, in the neighboring ring. As by being straight in cross-section and so presenting straight surfaces to the corresponding straight-in-cross-section radially outer surfaces of the segments, or in any other way so that the means aforesaid applies yielding resistance to the expansion of the series to portions thereof in planes remote from each other and transverse of the axis of the series, this annular medium embracing the segments and herein shown for example as three rings allows the segments to move radially inward or outward substantially without tilting or rocking out of parallelism with the axis of the throat, *i. e.*, out of parallelism with their rest positions, for each spring is rigid from one of said planes to the other.

To stiffen the rings, I may bend each of them continuously to form a channel or

crimp, as shown at *o* in Fig. 4, the channels coinciding with each other and with a continuous groove *p* formed exteriorly of and in the series of segments. By this means the parts comprising the device, to wit, the segments and rings, will be interlocked with each other. The rings, as shown, preferably each have greater width than thickness.

10. So far as I am aware it is new in this art to utilize substantially concentric spring rings as the resistance means; and this has the advantage over a single ring of the same thickness of greater susceptibility to yield.
15. I therefore claim such substantially concentric spring rings broadly, *i. e.*, without reference to whether or not the form of said means and its relation to the segments is such as to prevent or substantially prevent 20 their tilting.

Having thus fully described my invention, what I claim as new and desire to secure by Letters Patent is:—

1. The combination of an annular expandable throat-forming series of segments and means to apply, to portions of said series in planes remote from each other and transverse of the axis of the series, yielding resistance to the expansion of such series including a spring ring embracing said series and cut by both said planes and being rigid from one such plane to the other.
2. The combination of an annular expandable throat-forming series of segments and

means to oppose yielding resistance to the expansion of said series including substantially concentric spring rings.

3. The combination of an annular expandable throat-forming series of segments and means to apply, to portions of said series in planes remote from each other and transverse of the axis of the series, yielding resistance to the expansion of such series including a spring ring embracing said series and cut by both said planes and being rigid from one such plane to the other, and another spring ring substantially concentric with and embracing the first ring.

4. The combination of an annular expandable throat-forming series of segments and means to apply, to portions of said series in planes remote from each other and transverse of the axis of the series, yielding resistance to the expansion of such series including a spring ring having greater width than thickness and embracing said series and cut by both said planes and being rigid from one such plane to the other, said ring having an annular crimp formed therein.

5. The combination of an annular expandable throat-forming series of segments and means to oppose yielding resistance to the expansion of said series including laminated concentric spring rings interlocked with each other against slippage relatively to 65 each other in one direction.

In testimony whereof I affix my signature
AMOS CALLESON.
